5 Claims. (Cl. 216—54)

The subject of the present invention is apparatus for applying revenue duty labels or like strips to the narrow sides of packages by means of adhesive.

5 Most of the known apparatus of this kind operate in such manner that the revenue duty label, to which adhesive has previously been applied, is brought by means of grippers or the like into the delivery track of the packages, so that 10 it is caused to bear against the package at the ends, whereupon, in the further course of the delivery movement of the package, the revenue duty strip is applied to its longitudinal sides, and, if desired, is also pressed on to the rear 15 side. Various devices have been proposed for obtaining a uniform, firm pressing of the part of the revenue duty strip which is applied to the end-sides of the package, for example automatically controlled rams or flexible counter 20 surfaces. In other cases, by means of special devices the revenue duty label is relatively strongly stretched between tongs, so that to a certain extent it is itself a temporary abutment.

All these devices complicate and increase the 25 cost of the construction of the machine, and moreover they reduce the working speed of the machine. The flexibly receding supporting surfaces generally require a lateral turning of the movement of delivery, while, on the other hand, 30 difficulty is experienced in obtaining the correct tension of the strip between the tongs, as unduly great tension can lead to tearing, while if the adjustment is too loose, creases may form when the strip is attached.

35 Now, in order to avoid the aforesaid disadvantages, according to this invention the procedure is such that, in a continuous guide track the foremost package is brought into and kept temporarily in such a position that it serves as 40 a supporting surface for the strip to be secured to the end of the following package, and which on the further advance movement is pressed in known manner on the longitudinal sides and, if desired, also on the rear side of the package. 45 Thus it becomes possible to complete the application of revenue duty labels on the packages in question in a single rectilinear path, while at the same time it is possible to dispense with special pressing devices of the type specified 50 above and also to simplify the type of construction.

Devices of widely varying type can be used. A typical example of such an apparatus for applying revenue duty labels is illustrated in the 55 annexed drawings, in which:

Fig. 1 is a side view of an apparatus for applying a revenue duty label.

Fig. 2 is a plan of the machine.

Fig. 3 is a plan of an additional device on a machine for applying a revenue duty strip, for 5 applying the ends of the said strip to the rear narrow sides of the package.

In the machine shown, the revenue duty strips are accommodated in a swinging container *a*, below which is located a revolving segmental 10 roller *b* provided with a bar or segment *c*. At the side of the roller *b* there is fitted a glue container *d* and a gluing roller which, when the roller *b* revolves, comes into contact with the projecting segment *c* and applies glue thereto. 15 On the further rotation of the roller *b* the segment *c* engages the swinging container *a* and makes rubbing contact with the lowermost strip in the container. Thus the bottom revenue duty strip is removed from the container *a* and ad- 20heres to the bar *c*.

Spaced apart at one side of the roller *b* there are provided gripper jaws *e* which swing up and down, and which are controlled in such manner that in their raised position they seize the ends 25 of the revenue duty strip which project laterally from the segment *c*, and move downwards on to a delivery table *f* in the path of the packages *g* to which the revenue duty strip is to be applied.

At the end of this downward movement, the 30 revenue duty strips arrive on bearing surfaces *h* which are fitted at the side of the delivery track of the package *g* and are placed endwise on the revenue duty strip. The surfaces of application are arranged adjustably so that the revenue duty 35 strips can be secured somewhat higher or lower on the edge of the box. To the bearing surface *h* for the revenue duty strip there is connected a guide track *k* provided with brushes and effecting for the lateral brushing of the ends of the 40 strips.

For advancing the packages *g* there is provided a conveyer device in the form of an endless conveyer chain *m* on which abutments *n* are 45 pivotally fixed. These abutments *n* are guided in a recess in the table *f* which extends to the immediate vicinity of the entrance of the guide channel *k* and there is interrupted by a transversely disposed recess *o*. As soon as the abut- 50 ments arrive at this recess the constraint ceases, and on the further movement of the conveyer chain *m* the abutments can swing freely downwards, leaving the package *g* in the advanced position in each particular case, in 55

which its rear side is, for instance, located behind the revenue duty strip.

The mode of operation of the apparatus is as follows: The revenue duty strip removed from the segmental roller *b*, by means of the gripping tongs *e*, is placed edgewise on the bearing surface *h*, and kept there until the advanced package strikes against the revenue duty strip. The jaw of the gripper is controlled by a cam *p* in such manner that, in the lower position, the jaw is open, so that when the package strikes the revenue duty strip, the ends of the latter can slide out of the jaws until the box with the freshly coated revenue duty strip strikes directly against the previously treated box. Thus the end of the revenue duty strip is pressed quite smooth, while on the intermittent further movement of the package *g* in the channel *k* the revenue duty strip is brushed firmly on both sides. The box remains for the time being at the entry of the channel in the position shown in Fig. 1, until the operation has been repeated and a new box comes into position and thrusts the previously agglutinated box further forward. Finally, at the end of the table the boxes fall on to a conveyer belt which carries out the further conveyance.

If it is necessary for the ends of the revenue duty strip to be secured also to the rear side of the box, there may be provided for this purpose knives *q* which are guided on both sides of the guide track *k*, and which are advanced laterally in succession by means of a cam device or the like; thereby the projecting ends of the strip are pressed against the rear side of the package, as shown in Fig. 3.

The invention is not limited to the form of constructions shown in the drawings, but other known devices may be used for feeding the revenue duty strip, for advancing the packages and also for pressing the strips against the sides and also against the rear wall; the main essential is their arrangement and co-ordination with one another so that they bring the foremost package into and keep it temporarily in such a position that it can serve as a supporting surface for the strip to be secured to the end-side of the following package.

I claim:

1. In a strip applying machine for packages, a table having a guide track thereon interrupted on an intermediate point providing a gap in the track, a strip magazine pivoted above the track, a combined glue applying and strip removing roller cooperating with the magazine, reciprocating grippers operable between said roller and said grip for transferring glued strips from the roller into vertical position in said gap across the guide tracks, and means for intermittently feeding packages along said track and against the glued strip between said grippers, to apply the glued strip to the package during the feeding of the latter along said track.

2. In a strip applying machine for packages, a table having a guide track thereon having a gap in the track, a strip magazine pivoted above the gap in the track, a segmental roller beneath the magazine for cooperative movement therewith to apply glue to the lowermost strip and remove the same from the magazine, laterally spaced grippers mounted for reciprocation between the roller and the gap for engaging the ends of the strip and transporting the same from the roller to the gap

across the guide track, and package feeding means for advancing the packages one at a time along the guide track and against the strip to apply the strip to the package and withdraw the strip under tension from said grippers.

3. In a strip applying machine for packages, a table with a guide track thereon, a strip magazine pivoted over the table, a segmental roller beneath the magazine for cooperative movement therewith to glue and remove the lowermost strip, a pair of spaced grippers mounted for reciprocation between the roller and the table for carrying strips from the roller to the table, supporting means on the guide track for engaging the lower edge of the strip and holding it across the track, and feeding means for passing packages one at a time through the track and against the supported strip to apply the strip to the package during the feeding thereof.

4. Apparatus for applying strips to the narrow sides of packages, comprising a table, a longitudinal guide track on said table, said table having a transverse opening intermediate its ends to form a gap in said guide track, a strip magazine pivoted above said table, mechanism cooperating with said magazine for applying adhesive to the lowermost strip in said magazine and for removing the same therefrom, gripper means mounted for reciprocation between said mechanism and said gap for engaging the ends of the glued strip and for transferring said glued strip from said mechanism to a vertical position in said gap across said guide track, and conveyor means for intermittently feeding packages longitudinally along said guide track against the glued strip between said gripper means whereby said strip is removed from said gripper means by the moving package and applied to the front edge and sides thereof, said conveyor means releasing each conveyed package at a point where the rear edge of the latter lies immediately adjacent said gap and forms an abutment surface for the following package.

5. Apparatus for applying strips to the narrow sides of packages, comprising a table, a longitudinal guide track on said table, said table having a transverse opening intermediate its ends to form a gap in said guide track, a strip magazine pivoted above said table, mechanism cooperating with said magazine for applying adhesive to the lowermost strip in said magazine and for removing the same therefrom, gripper means mounted for reciprocation between said mechanism and said gap for engaging the ends of the glued strip and for transferring said glued strip from said mechanism to a vertical position in said gap across said guide track, conveyor means for intermittently feeding packages longitudinally along said guide track against the glued strip between said gripper means, whereby said strip is removed from said gripper means by the moving package and applied to the front edge and sides of said package, said conveyor means releasing each conveyed package at a point where the rear edge of the latter lies immediately adjacent said gap and forms an abutment surface for the following package, lateral brushes for pressing the strip to the longitudinal sides of the package, and means movable into said gap for pressing the strips to the rear edge of the package.

EDMUND ZIMNIAK.
